Frank Booth Jammie Harvey

UNITED STATES PATENT OFFICE.

DAVID W. BROOKS, OF NEW YORK, N. Y., ASSIGNOR TO CONCRETE STEEL COMPANY, OF NEW YORK, N. Y., A CORPORATION OF DELAWARE.

CONCRETE-INSERT.

1,272,909.

Specification of Letters Patent. Patented July 16, 1918.

Application filed January 3, 1918. Serial No. 210,152.

To all whom it may concern:

Be it known that I, DAVID W. BROOKS, a citizen of the United States of America, residing in the city, county, and State of New York, (whose post-office address is 42 Broadway, New York city, New York), have invented an Improvement in Concrete-Inserts, of which the following is a specification.

This invention relates to improvements in what are generally called concrete inserts. Such devices may be embedded in the ceilings or walls of concrete structures for the purpose of fastening hangers, brackets or the like. The principal objects of the invention are to provide an insert which will possess maximum strength with the use of a minimum amount of metal, and which may be used as a unit and assembled with others of the same type to enlarge the possibilities of use of the insert. Other objects will appear from the following description.

A preferred embodiment of the invention has been selected herein for purposes of illustration and description, the same being shown in the accompanying drawing, wherein,

Figure 1 is an end elevation of the insert, Fig. 2 is a side elevation,

Fig. 3 is a vertical cross-section on the line 3—3 of Fig. 2 showing a bolt in position,

Fig. 4 is a plan view of the underside of the insert,

Figs. 5 and 6 are detail views later to be referred to, and

Fig. 7 is a side elevation of two inserts set end to end.

Referring to the drawings the insert comprises a hollow body portion 10 having upwardly extending retaining ears 11 which are flared outwardly for a purpose which will be later referred to. The side walls 12 of the insert have inwardly extending flanges 13 upon which the head of a bolt or other retaining member is adapted to rest. Outwardly extending flanges 14 are provided for a purpose which will later be referred to. The lower face 15 of the insert is adapted to rest upon the centering before the concrete is poured and the insert may be held in place by nails driven into the centering and engaging recesses 16 shown in Fig. 4.

It is the usual practice to place an insert 55 of this type upon the centering before the

concrete is poured around it and to position the insert upon the centering so that it will occupy the proper position when the concrete is set. It is therefore highly preferable that concrete is prevented from flowing into the interior of the insert where it is intended later to insert the head of a bolt or the like. Previous practice with respect to inserts of this type has involved the extension of the body of the insert beyond a point where any strains are transmitted from the hanging bolt through the insert to the concrete, in order that the only opening may face downwardly. This entails the use of a comparatively large amount of metal which does not contribute to the strength of the insert except to a very slight extent.

The body of the insert here shown is substantially uniform in cross-section throughout its length and its ends are squared. In order to prevent the concrete from flowing into the interior of the insert end caps 17 are provided which are preferably made of thin light metal and may be easily formed by any well known stamping process. These end caps are shown to best advantage in Figs. 5 and 6. They are formed with side walls 18 which have a slight flare in order that the cap may be held in position when inserted in the end of the body portion of the insert as shown in Fig. 2. The end caps are provided with a flange 19 which will rest upon the centering and prevent concrete from flowing into the inside of the body. These end caps may be of any preferred shape or size the only requisite being that at least one end shall be closed by a cap which will permit the insertion of a bolt head after the insert has been set in the concrete and the centering removed. It is preferable that both ends be closed in the same manner, both from the point of view of convenience in inserting the hanging bolt and as minimizing the number of parts which must be carried in stock to supply the demand of inserts for this type. The end of the caps is preferably rounded as shown at 20 in Fig. 5 in order that the amount of concrete surrounding the insert may be lessened as little as possible.

It has been observed as a result of experiment that when abnormal strains are placed upon an insert a cone of concrete is pulled out and that the sides of the cone form an angle of substantially 45° with the

normal surface of the concrete. This may be termed a sheer line or line of cleavage. In order to increase the area of cleavage surface and therefore increase the hold of the 5 insert on the concrete the ears 11 are flared outwardly to distribute the strain between a point where the pull necessary to draw the insert from the concrete is substantially equal to the pull which can be resisted by 10 the metal of the insert itself; thus developing the full strength of the insert.

When the insert is in operative position there is a downward strain upon the bolt 21 which is resisted by the internal flanges 13 15 and transmitted through them to the body and ears of the insert. In the absence of any transverse connections between the sides 12 of the body portion there may be a tendency to bend the internal flanges downward. To resist this tendency the external 20 flanges 14 are provided and it will be observed from an examination of Fig. 3 that any sagging of the flanges 13 will tend to press the flanges 14 against the body of concrete. It is well known that the compression 25 strength of concrete greatly exceeds its tension strength and the flanges 14 are so formed that any downward strain upon the flanges 13 will tend to compress the concrete 30 above the flanges 14.

The requirements of building construction call for a great variety of sizes and shapes of concrete inserts. The principal variation in demand is in the length of adjustment 35 and the possibilities of positioning the hanging bolt 21. In other words certain constructions may require inserts having slots of varying length which are otherwise the same. The insert herein shown is admirably adapted to provide for such a situation in that it may be used as a unit to build up 40 an insert having a long slot, that is a greater range of adjustment. As shown in Fig. 7, two of the inserts previously described may 45 be set end to end, secured to the centering and end caps inserted only in the exposed ends of each insert. Obviously any number of these inserts may be set up in this way to provide a slot of a length which will meet 50 the requirements of the situation.

It will be understood that the illustrative embodiment of the invention herein shown may be variously modified and the invention may be variously embodied within the scope 55 of the subjoined claims.

I claim as my invention:

1. An insert for concrete having a body

portion substantially uniform in cross-section throughout its length provided with inwardly projecting hanger engaging flanges 60 integral with said body portion, and end caps adapted to close partially the end openings of said body portion and thereby provide an entrance passage for a hanger.

2. A concrete insert having a body portion formed with inwardly extending hanger engaging flanges and upwardly extending concrete engaging means, said body portion, flanges and concrete engaging means being formed of heavy strain resisting 70 metal, and caps of relatively light metal for said insert, said caps forming entrance passages.

3. A multiple insert for concrete comprising a plurality of similar units adapted to 75 be set end to end, each unit comprising an open ended body portion of substantially uniform cross-section and provided with internally projecting hanger engaging flanges 80 abutting the flanges of an adjacent unit, and end caps adapted to close the open ends of the outside units while providing an entrance passage for a hanger.

4. A concrete unit having a body portion provided with internally extending hanger 85 engaging flanges, upwardly extending concrete engaging means, said body portion being open at one end, and an end cap adapted to close said open end except for a passage-way through the plane of the base of the in- 90

5. A concrete insert having a body portion provided with internally extending hanger engaging flanges, upwardly extending concrete engaging means, said body portion 95 being open in a plane substantially at right angles to the base of the insert, and an end cap to close said opening and to provide an entrance passage from the base plane of the insert. 100

6. A concrete insert having a body portion provided with internally extending hanger engaging flanges, upwardly extending concrete engaging means, said body portion being open at one end, and a cap of resilient material adapted to be inserted in the open end of the body portion and to frictionally engage the side walls thereof by the outward pressure upon the inner surface of said walls. 105

In testimony whereof, I have signed my 110 name to this specification this 2nd day of January, 1918.

DAVID W. BROOKS:
